SMOKING STAND

John P. Jansma, Broadview, Mont.

Application May 22, 1950, Serial No. 10,092

Term of patent 14 years

(Cl. D85—2)

To all whom it may concern:

Be it known that I, John P. Jansma, a citizen of the United States, residing at Broadview, in the county of Yellowstone and State of Montana, have invented a new, original, and ornamental Design for a Smoking Stand, of which the following is a specification, reference being had to the accompanying drawing, forming part thereof.

Fig. 1 is a perspective view of a smoking stand, showing my new design;

Fig. 2 is a vertical sectional view approximately on line 2—2 as indicated in Fig. 3; and

Fig. 3 is a cross-sectional view thereof taken on line 3—3 of Fig. 2.

I claim:

The ornamental design for a smoking stand, substantially as shown.

JOHN P. JANSMA.
